UNITED STATES PATENT OFFICE.

CORNELIUS B. DEMAREST, OF BROOKLYN, NEW YORK.

FOLDING CHAIR.

SPECIFICATION forming part of Letters Patent No. 396,271, dated January 15, 1889.

Application filed March 6, 1888. Serial No. 266,338. (No model.)

To all whom it may concern:

Be it known that I, CORNELIUS B. DEMAREST, a citizen of the United States, residing at Brooklyn, in the county of Kings and State 5 of New York, have invented certain new and useful Improvements in Folding Chairs, of which the following is a specification, reference being had therein to the accompanying drawings.

10 The objects of my invention are to produce a chair suitable for places where space is limited and valuable, and especially adapted for use in Sunday-schools where the teachers have to face forward during general exercises and 15 face back toward their classes while instructing them.

It relates to a folding chair in which both the seat and the back are moved to the positions required for sitting purposes and for 20 easy ingress and egress to and from seats placed in rows, and is an improvement upon the chair shown in Patent No. 197,723, granted to me December 4, 1877; and it consists in the several devices and combination of parts for 25 obtaining these ends, as hereinafter described and claimed.

In the drawings, Figure 1 represents, in perspective, a row of chairs having attached to the back of one of them, in a folded position, 30 a chair constructed in accordance with my invention. Fig. 2 is a perspective view of the same, showing the back chair open. Fig. 3 is a horizontal section on line x x of Fig. 1.

In said drawings, A represents the legs or 35 standards of a chair or settee, having the sides B of the back B', as well as the support B² for the arms C, formed integral with the standards. To the upper end of said standards are pivoted the brackets d, to which is secured the seat D, so that the latter can be 40 folded when desired against the front side of the back B'. To permit Sunday-school teachers to be facing forward during general exercise, or to be facing back while instructing 45 their classes; and at the same time to be seated without disturbing the adjoining classes, the back of every fifth or sixth chair of a row is

provided with a pair of standards, E, preferably cast integral with the standards and sides B of said chair.

To the upper end of the standards E, or it may be to lugs projecting rearwardly from the upper end of the sides B of the primary or front chair, is pivoted, at e, the upper end of the sides F, carrying the back f of the extra, secondary, or rearwardly-projecting chair. To the lower end of the sides F are pivoted, at f², the supports g for the seat G, the pivots f² passing through said supports about one-third of the distance from their rear end, and 60 from said rear ends a pin or lug, g², projects laterally and is made to enter a groove, e², in each of the standards E. Said grooves are substantially vertical, but preferably slightly curved, to throw the end of the support having the lug g² somewhat outwardly to facilitate the retention of the seat G when closed, and also to cause it to extend farther out when open.

Having now fully described my invention, I 70 claim—

1. In combination with a chair, a secondary chair having the upper end of its back pivoted to the back of the primary chair, and its seat having a hinge-connection with the 75 back of the secondary chair, and also a sliding hinge-connection with the frame of the primary chair.

2. The combination of a chair having a seat and sides supporting the back thereof and 80 secured to the rear of said sides, and a frame, E, having grooves therein, with a secondary chair-back having its sides pivoted to said frame and a seat having its supports pivoted to said sides, and lugs on the ends of said 85 supports received within the grooves of the frame E, substantially as and for the purpose described.

In testimony whereof I affix my signature in presence of two witnesses.

CORNELIUS B. DEMAREST.
